UNITED STATES PATENT OFFICE.

WILLIAM A. RANDOW, OF DENVER, COLORADO.

LOCOMOTIVE-CAB SEAT.

SPECIFICATION forming part of Letters Patent No. 582,799, dated May 18, 1897.

Application filed January 19, 1897. Serial No. 619,798. (No model.)

To all whom it may concern:

Be it known that I, WILLIAM A. RANDOW, a citizen of the United States of America, residing at Denver, in the county of Arapahoe and State of Colorado, have invented certain new and useful Improvements in Locomotive-Cab Seats; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in locomotive-cab-chair seats; and the objects of my invention are, first, to provide a locomotive-cab chair the seat of which is spring-cushioned; second, to provide a cab-chair having a folding seat; third, to provide a cab-chair having a folding arm-rest. I attain these objects by the mechanism illustrated and described in the accompanying drawings and specification, in which—

25 Figure 1 represents a vertical cross-section of my improved cab-chair, showing the chair in a folded position; Fig. 2, a side elevation of the same attached to the side of a cab and showing the chair in an open position; Fig. 3, a front elevation; Fig. 4, two fragments in perspective of a pivotal joint of the arm-rest and one of its supports; Fig. 5, a fragment in perspective of the seat-supporting mechanism, and Fig. 6 a fragment in perspective of the lower wall-support and lower end of the chair.

Similar letters and figures of reference refer to similar parts throughout the several views.

Referring to Fig. 1, A designates the seat, and B the arm-rest.

C is a thin metal plate which I secure to the side of the cab by screws C', the side outlines of the cab being designated by the dotted lines D. To this plate I secure in a vertical position two yoke-shaped strips E and F, at a short distance apart, by rivets G. The ends of these strips are bent at right angles away from the plate. Extending across the under side of the top part of these strips is a strip H, which is held up against them by the top of the springs I and J, which bear against the under side of it. These springs rest on the

lower ends of the strips E and F and are confined to them by the bolts K and L, which pass freely through both ends of the strips 55 and also through the cross-strip H. Consequently this cross-strip is free to move down and compress the springs independent of the vertical strips and of the plate. The ends of this cross-strip are bent down and are riveted 60 with the top ends of the cross-braces M and N to the side standards O and P, the bottom ends of which are riveted to the lower ends of the cross-braces M and N. Consequently the standards, the cross-braces, and the cross-piece comprise a rigid frame. On the lower end of the standards I place staples Q, which fit loosely, and secure them to a plate R, which is also secured to the side of the cab by screws S. To the turned-down ends U of 70 the cross-piece H, I secure an angle-plate V, one to each vertical end, by screws W, (see Fig. 4,) and to these angle-plates I rivet vertical strips X, and to the tops of these strips I secure by rivets hinge-pieces Y, which are 75 provided with a T-slot Z or eye, in which fits a T-shaped pin 1, which is formed on the end of the straps 2. These strips are secured to a strip of wood B, which forms an arm-rest. The form of the pins 1 is such that they must 80 be inserted in the eyes before they are secured to the arm-rest, and when the arm-rest is swung down in a position of use the straps rest on the top of the vertical strips X and hold it at right angles to the vertical strips X, 85 as shown in Fig. 2.

In the tops of the standards O and P, I form slots 4, and in these slots I pivot to slide freely up and down angled levers 5 and 6, which support the strip of wood A, which forms the 90 seat, the seat being secured to them by rivets 8. In the lower edge of these angled levers I form a slot 9 in which I pivot one end of a forked lever 10, the opposite end of which is pivoted to the lower end of the standards and 95 the cross-braces, the ends of these cross-braces being carried under and bent up on the opposite side of the standards to form a shoe. The forked lever 10 is formed of the pieces 11 and 12, the piece 11 being riveted to the piece 100 12 near its lower end. The plate R is secured to the side of the cab in a position to stand about two or three inches above the floor-line D'. All of the mechanism of the chair ex-

cept these plates and the vertical strips E and F are supported by the springs, and when the seat is not in use it is folded up, as shown in Fig. 1, which is accomplished by moving 5 the rear end of the seat or its angled levers up in the slots in the standards and moving the forked levers 10 in toward the standards until they stand parallel with them. The arm-rest may also be moved into a vertical 10 position. When the seat is to be used, it is swung out, as shown in Fig. 2, by moving the angled seat-levers down in the slots in the standards and the levers 10 out to the ends of the slots in the lower edges of the angled levers. The arm-rest is also swung down to a 15 position of use, and when the seat is occupied the entire weight of the occupant is carried by the springs, which makes a resilient cushion at all times independent of the jolting of the locomotive. The seat is preferably situated 20 in the cab relative to the cab-window to allow the arm-rest to swing down over the window-sill, which is designated by the dotted line 13. When the window is open, by 25 this arrangement the seat occupies but very little space along the side of the cab, and it provides for the engineer and fireman a comfortable spring-cushioned seat and arm-rest of simple and durable construction. Both the 30 seat and arm-rest may be upholstered, if desired.

I do not wish to be limited to the exact construction shown and described, as many changes might be made without departing 35 from the spirit of my invention.

Having described my invention, what I claim as new, and desire to secure by Letters Patent, is—

1. In a locomotive-cab seat the combination 40 of the side standards the main supporting-plate and foot-plates, vertically-arranged yoke-shaped strips secured to said main plate, compression-springs secured to said vertical

yoke-shaped strips and secured against displacement therefrom, a cross-strip arranged 45 to rest freely on the top of said springs and adapted to be held resiliently against the under side of the top of the vertical yoke-shaped strips by said springs, with a seat pivotally secured to said cross-piece and adapted to 50 swing downward and upward into vertical and horizontal positions and an arm-rest adapted to be supported by said cross-piece and springs, and adapted to pivotally swing into vertical and horizontal positions, substantially as described. 55

2. The combination with the supporting-plates of the springs, the cross-strip resting thereon, the cross-braces and the oppositely-disposed standards secured to said cross-strip 60 and having slots in their top ends, angled levers pivoted to move in said slots and supporting a seat, slots in said angled levers and levers pivoted at one end in said slots to move therein and pivoted at their opposite ends to 65 the bottom of the said standards and cross-braces, substantially as described.

3. The combination of the supporting-plates, the springs the cross-piece resting on said springs, the standards, the seat-supporting angled levers, the seat, the levers extending from said seat-supporting levers to the bottom of said standards, the cross-braces and the vertical strips secured to said cross-piece, a hinge-eye secured to the top of said 75 vertical strips and an arm-rest having a hinge pin and strap pivoted to said hinge-eye and adapted to swing from a horizontal to a vertical position, substantially as described.

In testimony whereof I affix my signature 80 in presence of two witnesses.

WILLIAM A. RANDOW.
